UNITED STATES PATENT OFFICE.

WORTHINGTON BROWN, OF HANNIBAL, MISSOURI.

DESIGN FOR A TRACE-FASTENER.

SPECIFICATION forming part of Design No. 28,741, dated May 31, 1898.

Application filed April 26, 1898. Serial No. 678,914. Term of patent 7 years.

To all whom it may concern:

Be it known that I, WORTHINGTON BROWN, of the city of Hannibal, Marion county, State of Missouri, have invented a new and original Design for Trace-Fasteners, of which the following is a full, clear, and exact description, reference being had to the accompanying drawing, forming a part hereof.

The figure is a perspective view of a trace-fastener embodying my design.

As shown in the drawing, the leading or material feature of my design consists of a flat plate or body 1, having an ornamented rear end 2, the forward end of said plate 1 being formed into a wedge-shaped open-bottomed head 3, the sides of which head are perforated,

and extending outwardly from the upper forward edge of said wedge-shaped head 3 is a semicircularly-curved arm 4, upon the end of which is a pointed lug or pin 5. Between 20 the head 3 and the curved arm 4 is an offset or shoulder 6.

I claim—

The design for a trace-fastener, substantially as herein shown and described. 25

In testimony whereof I affix my signature in presence of two witnesses.

WORTHINGTON BROWN.

Witnesses:

A. J. McCauley,
M. P. Smith.
